INCLINATION INDICATING DEVICE

Leonidas C. Miller, Dallas, Tex.

Application May 18, 1939, Serial No. 274,329

4 Claims. (Cl. 33—205.5)

This invention relates to new and useful improvements in inclination indicating devices.

In the drilling of wells, it is not unusual for the drill bit to be deflected from its course during the drilling operation, such deflection being caused by inclined strata, or other causes. If the well bore is being drilled on a true vertical line, this results in said bore inclining from the vertical and in some instances, successive deviations or variations may interfere with continued drilling and also with subsequent pumping operations. If angular drilling is being done, a slight deflection or deviation from the intended course of the drill bit may result in an erroneous curvature or angularity of the well bore, with the result that the producing formation is missed entirely and never penetrated by the bit. For these reasons, it is not only desirable, but practically essential that the driller check the inclination of the bore hole from time to time as drilling proceeds so as to be advised of the inclination from the vertical of said bore.

It is, therefore, one of the objects of this invention to provide an improved device which will accurately indicate and record the deviation or "drift" of a bore hole from the vertical, whereby the drilling may be performed in accordance with such indications to drill the bore in a desired manner and at the desired inclination.

Another object of the invention is to provide an improved inclination or drift indicator wherein a photographic record of the angle of inclination from the vertical is made, the photographing operation being controlled by a time mechanism, whereby the device may be set at the surface and lowered into the bore hole to automatically record the inclination at the desired elevation.

A further object of the invention is to provide an improved indicating device of the character described, wherein photographic printing out proof paper, or other light sensitive paper is employed for receiving the indication of the inclination of the bore; the use of such paper eliminating the necessity of a developing process and greatly facilitating practical use of the device in the field.

Still another object of the invention is to provide an improved device, of the character described, wherein the lens for focusing light rays onto the photographic paper is universally mounted within an outside casing, whereby the lens assumes a vertical position at all times irrespective of the inclination of the outer casing; the angle between the lens and the casing

5 indicating the angle of inclination of the casing, and the bore within which it is lowered, such angle being recorded on the photographic paper to record the inclination or drift of said bore from the vertical.

A particular object of the invention is to provide an indicating device, of the character described, having a time controlled mechanism associated with the photographing means, whereby 10 the time at which the device is actuated and also the duration of the photographing operation may be readily and accurately controlled.

A still further object of the invention is to provide an improved inclination indicating device 15 which may be run into the bore hole on a flexible line to facilitate the lowering thereof; said device having a protective housing therearound to prevent damage to said device during its travel through the well bore.

20 A construction designed to carry out the invention will be hereinafter described, together with other features of the invention.

The invention will be more readily understood from a reading of the following specification 25 and by reference to the accompanying drawings, in which an example of the invention is shown, and wherein:

Figure 1 is an elevation of an indicating device, constructed in accordance with the invention, and showing the device mounted within a protective housing, whereby it may be readily lowered through the well bore.

Figure 2 is an enlarged view, partly in elevation and partly in section, of said indicating device.

35 Figure 3 is a transverse, vertical, sectional view, taken on the line 3—3 of Figure 2.

Figure 4 is a view, similar to Figure 3, showing the upper portion of the device, said view being 40 taken from the opposite side illustrated in Figure 2.

Figure 5 is an enlarged, horizontal, cross-sectional view, taken on the line 5—5 of Figure 2.

Figure 6 is an enlarged, horizontal, cross-sectional view, taken on the line 6—6 of Figure 2.

45 Figure 7 is an enlarged, transverse, vertical, sectional view, showing the parts illustrated in Figure 3, which parts comprise the timing mechanism.

50 Figure 8 is a view of the lower portion of the device, showing the position which the device would assume in an inclined bore.

Figure 9 is a horizontal, cross-sectional view, taken on the line 9—9 of Figure 7, and

Figure 10 is a view of the lower portion of

the device, showing a slightly modified form of lens arrangement.

In the drawings, the numeral 10 designates an elongate tubular casing which is preferably constructed in three sections, A, B and C. The section A has the upper end of its bore internally screw-threaded and is coupled to the intermediate section B by means of a coupling block 11 and collar 11a. The upper end of the intermediate section B is connected to the uppermost section C by means of a coupling member or collar 12. The upper end of the section C is closed by a suitable collar 13, which may be suitably secured to said upper end. The outer periphery of the collar 13 has its upper portion screw-threaded to receive a cap member 14. The upper section C houses the timing mechanism, as will be herein-after explained, while the intermediate section B receives dry cell batteries 15. The lowermost section A houses the photographic mechanism and has its lower end normally closed by an end cap or plug 16, which is threaded into said lower end so as to be readily removable.

The block 11 which is secured within the upper end of the lowermost section A is formed with an axial bore 17 within which an electric lamp 18 is mounted. The base of the lamp rests on an internal, annular shoulder 19 which is formed within the bore 17, whereby said lamp is suitably supported within the block and has its globe depending into the bore of the section A. The lamp 18 is retained in position within the bore 17 by a spring-pressed contact plunger 20, which plunger is mounted within an axial opening 21 formed in an insulating block 22. The block 22 is suitably mounted within the coupling collar 11a, as is clearly shown in Figure 2. The plunger 20 is tubular and has a coiled spring 23 confined therein. The upper end of the spring 23 engages the underside of a contact disk 24, which disk is secured to the upper end of the insulating block 22. Since the tubular plunger 20 is slideable within the block, while the contact plate 24 is fixed to said block, it will be manifest that the coiled spring exerts its force to urge the plunger downwardly into engagement with the end contact of the electric lamp 18. Any desired number of dry cell batteries 15 may be mounted within the intermediate section B and the lowermost battery has its end contact engaging the contact disk 24, whereby when the electrical current flows through the disk 24, coiled spring 23, plunger 20 and to the lamp 18. Therefore, when the circuit to the batteries 15 is closed, the lamp 18 is illuminated.

An elongate, tapered or conical sleeve or tubular pendulum 25 is mounted within the lowermost section A below the electric lamp 18 and this sleeve or tube extends substantially throughout the length of the section A. The upper end of the sleeve or tube is enlarged and is gradually tapered or reduced toward its lower end, as is clearly shown in Figure 2. The upper end of the sleeve is mounted, by means of a Cardan suspension, within a depending flange 26, which is preferably formed integral with the coupling block 11. The suspension includes a ring 27 which encircles the upper end of the sleeve or tube, being interposed between said sleeve and the depending flange 26. The ring 27 is secured to the flange 26 by means of radially extending pins 28, which pins extend through openings 29 provided in said ring (Figure 5).

Each pin has a point contact with the bore of the opening 29, whereby the ring may be swung with relation to the flange 26.

The ring 27 is also connected to the upper end of the sleeve or tube 25 by means of additional pins 30. The pins 30 have their outer ends secured in the ring 27, while their inner ends extend through openings 31 formed in the sleeve or tube 25. The pins 30 are constructed in substantially the same manner as are the pins 28, whereby the tube may undergo a swinging movement with relation to the ring 27. It is pointed out that the pins 30 are diametrically opposite each other, while the pins 28 are also disposed diametrically opposite each other. As explained, the mounting of the upper end of the tube is generally known as a Cardan suspension and permits a universal movement of the tube 25 with respect to the vertical wall of the section A. With this arrangement, the section A may be inclined from the vertical and the sleeve or tube 25 will always remain in a vertical plane, said tube acting as a plumb bob.

As is clearly shown in Figure 2, the lamp globe extends downwardly into the upper end of the sleeve or tube 25 and a condensing lens 32 is mounted within said sleeve immediately below the lamp globe. The lens 32 extends transversely across the bore of said sleeve and serves to collect the light rays emitting from the globe and focus them downwardly through the sleeve or tube onto a projection lens 33. The projection lens 33 is suitably mounted in the lower end of the sleeve or tube 25 and serves 35 to direct the light rays onto the upper end of the plug 16 which is threaded into the lower end of the section A.

The plug 16 has its upper end formed with an annular, peripheral flange or lip 34, whereby 40 a recess 35 is provided in the top of said plug. This recess is arranged to receive a disk 36, which disk is preferably constructed of a photographic printing out proof paper. Of course, the invention is not to be limited to this particular type of paper, as any light sensitive paper or material, capable of being developed by exposure to light, may be employed. The upper surface of the disk 36, as is clearly shown in Figure 6, includes a plurality of concentric circles 37 which are imprinted or otherwise displayed thereon. The center of the disk represents the true vertical plane and when the elongate sleeve or tube 25, which carries the lens 32 and 33 is disposed in a true vertical plane, 55 the light from the lamp 18 is directed exactly onto the center of the disk 36. When the tube 25 assumes a position at an angle from the vertical, the light rays are directed onto the disk off-center from said disk. The innermost circle 37 may represent one degree from the vertical, while the second circle may represent two degrees, the third circle three degrees and so on to the outer edge of said disk.

When the disk is placed in the top of the plug 16 and said plug inserted into the lowermost section A, said paper is unexposed. When it is desired to take a reading, the circuit to the electric lamp 18 is closed to illuminate the lamp. The light rays from the lamp pass through the lens 32 and then through the lens 33 and are concentrated at a given point on the disk 36. If the elongate lens carrying tube 25 is in a true vertical position, the light beam is concentrated on the center of the disk 36. This beam

striking the surface of the disk results in an exposure of said surface, which brings out a dot on the disk. The lamp 18 is illuminated for a sufficient length of time to expose or print out that portion of the disk on which the beam is concentrated.

If the outer casing A is at an incline, it will be manifest that the tube will be swung with relation to said outer casing, as is shown in Figure 8, with the result that the light beam from the lamp 18 will be directed onto one of the concentric circles 37 on the disk 36. When a reading is taken with the parts in this position, it will be manifest that the dot or point which has been exposed to the light beam will be off center of the disk 36. The position of the dot will indicate the angle of inclination of the outer casing from the vertical and, by removing the disk 36 and noting the position of said dot, it is possible to accurately determine the inclination of the outer casing at the time that the lamp 18 is illuminated.

For closing the electrical circuit through the batteries 15 to the lamp 18, the upper contact of the uppermost battery 15 is engaged by a spring-pressed plunger 38 (Figure 2). The plunger is slidable within an insulating block or collar 39, which is mounted within the coupling collar 12 which connects the intermediate section B with the upper section C. The plunger 38 is tubular and has a coiled spring 40 mounted therein. The upper end of the spring engages a metallic contact 41 which is mounted within the top of the insulating collar or block 39. The contact 41 is connected by a wire 42 with a metallic contact plate 43, which plate is mounted on a suitable insulated base 44. A contact screw 45 is threaded through the base and also through the plate 43, whereby said screw is adjustable relative to said plate. A contact arm 46 has its upper end fastened to a suitable bracket 47, which bracket is grounded to the metallic section C. When the contact arm 46 is swung inwardly to engage the contact screw 45, it will be manifest that an electrical circuit is completed from ground through the arm 46 and screw 45, then through the plate 43, wire 42 and contact 41 to one side of the battery 15. The other side of the battery is connected to the electric lamp 18, as has been described, and, thus, it will be seen that when the switch arm 46 is engaged with the contact screw 45 the lamp 18 is illuminated. By adjusting the screw 45, it is possible to control the amount of movement necessary before the arm 46 engages said screw to close the circuit.

For actuating the switch arm 46 to swing the same into engagement with the contact screw 45, an elongate rod 48 is provided. This rod has an annular projection 49 on its lower end, which projection is adapted to engage a projection 50 formed on the switch arm 46. By observing Figure 4, it will be seen that when the rod 48 is moved upwardly, the projection 49 on said rod strikes the projection 50 on the switch arm to swing said arm inwardly toward the contact screw 45 and thereby close the circuit. Lowering of the rod 48 will, of course, permit the spring contact arm 46 to return to its original disengaged position.

The upper end of the rod 48 is secured to a plunger 51, which is slidably mounted within the bore of a cylinder 52. The cylinder 52 is secured to one of the plates of the housing 53 of the timing mechanism T, as is clearly shown in Figure 7. A coiled spring 54 constantly urges the

plunger 51 and the operating rod 48 attached thereto upwardly. The upper end of the plunger 51 engages the periphery of a cam disk or wheel 55, which disk is secured to a rotatable shaft 56, 5 which shaft is driven by the timing mechanism T, as will be hereinafter explained. The cam disk is provided with a recess 57 (Figure 4) and, manifestly, when said recess moves opposite the plunger 51, said plunger is moved upwardly by 10 the coiled spring 54, whereby the operating rod closes the electrical circuit by swinging the contact arm 46 into engagement with the contact screw 45. As long as the upper end of the plunger remains in the recess 57 of the cam 55, the circuit to the lamp 18 remains completed and said lamp remains illuminated. As soon as the cam rotates sufficiently to move the upper end of the plunger 51 out of said recess, the plunger is depressed to again open the circuit, as has been 20 explained.

The shaft 56 on which the cam 55 is mounted extends through the side plates of the housing 53 of the timing mechanism T and has a gear 58 freely rotatable thereon. This gear has a clutch plate 59 secured to one side thereof and said clutch plate is adapted to be engaged by a second clutch plate 60 which is secured on the shaft 56. The clutch plates 59 and 60 provide for a frictional drive between the shaft 56 and the gear 58. 25 The gear 58 has connection through the usual gear train 61 with the escapement gear 62 of the timing mechanism. The escapement gear operates the escapement 63 in the usual manner and said escapement is, of course, connected with the usual balance wheel 64 of the timing mechanism. 30

For driving or rotating the shaft 56 to impart a rotation to the cam 55, a flat spring 65 has one end secured to said shaft while its other end is secured by means of a pin 66 to the inner wall 40 of the side plate 53. When the spring 65 is wound, the unwinding of said spring imparts a rotation to the shaft 56 and the speed of rotation of said shaft is controlled by the timing mechanism hereinbefore described. The connection between the shaft and the gears of the timing mechanism is set up by the frictional engagement of the clutch plates 59 and 60.

For winding the spring 65 and also for adjusting the cam 55, whereby said cam must rotate a predetermined distance before moving its recess 57 into registration with the plunger 51, the shaft 56 is extended beyond the clutch plate 60. This end of the shaft has a bevelled gear 67 secured thereto and this gear is in constant mesh with a pinion 68. The pinion 68 is mounted on a shaft 69 which is journaled in the collar 13 which closes the upper end of the section C. A suitable hand knob 70 is fastened to the upper end of the shaft 69 so that said shaft may be manually rotated.

By manipulating the knob 70 to rotate the shaft 69, it will be manifest that a rotation may be imparted to the shaft 56 through the gears 68 and 67. In this manner, the flat spring 65 may be wound a predetermined distance and also the cam 55 rotated to adjust the recess 57 relative to the upper end of the plunger 51, whereby the exact time of the upward movement of the plunger 51 and the resultant closing of the circuit to the lamp 18 may be accurately controlled. With this arrangement, it is possible to adjust the spring 65 and cam 55 at the surface and a predetermined amount of time will elapse before the lamp is illuminated, thereby making it possible to lower the device to a predetermined point

in the well bore before the indication is taken. The face of the gear 67 may be provided with a dial 67a (Figure 2) which is visible through a window 73 in the housing plate 53, whereby accurate adjustment may be readily made.

For limiting the rotation of the shaft and cam to one complete revolution, the bevelled gear 67 is provided with an extending stop pin 71 which is secured to its peripheral edge portion. This pin is adapted to engage a stop member or screw 72 which is threaded through the housing 53 above the window 73 in the upper end of the housing. It is manifest that the timing mechanism T may be of any desired construction and may be made to require any amount of time for one complete revolution of the cam 55. The device may be lowered into the well bore in any suitable manner, but it is preferable that the same be lowered on a wire line, whereby the time and labor required for such lowering is reduced to a minimum.

In Figure 1, the device 10 has been shown as mounted within an outer housing 75, which housing has its lower end closed by a plug 76. This plug is preferably encased within an outer rubber shield 77, which shield absorbs any shock of the housing 75 striking the side walls of the bore. An elongate tube 78 extends axially within the housing 75 and receives the device 10, said device being confined between spring-pressed plungers 79. The tube 78 is spaced from the bore of the housing 75 by means of resilient shock absorbing collars 80. The upper end of the housing is provided with the usual cable socket 81, whereby a cable or other flexible line 82 may be employed to lower said housing through the bore. With this arrangement, the device 10 is protected from damage and shock during the lowering operation.

In the operation of the device, the hand knob 70 is first rotated to adjust the cam 55 with relation to the plunger 51. This adjustment is made at the surface of the well and is in accordance with the time required for lowering the device to the point at which the reading is taken. An unexposed disk of the photographic paper 36 is inserted within the recess 35 in the plug 16. The device 10 is then placed within the housing 75 and is lowered through the bore of the well. As the lowering operation is performed, the timing mechanism T is rotating the cam 55, which cam has the plunger 51 engaging its periphery. At this time, the plunger is in its lowered position, as is the operating rod 48 secured thereto, with the result that the switch arm 46 is disengaged from the contact screw 50.

When the point at which a reading is to be taken is reached, the lowering of the device is stopped and said device remains suspended in the well bore. Obviously, if the bore at this point is inclined from a vertical plane, the housing 75, as well as the entire device 10, is inclined at the same angle. Due to the Cardan suspension of the lens tube 25, said tube swings to a true vertical position, regardless of the inclination of the outer casing of the device 10. As soon as the cam 55 has rotated sufficiently to move its recess 57 opposite the plunger 51, said plunger moves upwardly into said recess, being urged thereto by the spring 54. As soon as this occurs, the operating rod 48 moves upwardly, whereby the switch arm 46 is swung to engage the contact screw 50. As explained, the engagement of the contact arm 46 with the screw 50 closes the electrical circuit through the batteries 15 to the electric lamp 18, whereby said lamp is illuminated. The light rays

from the lamp 18 pass through the lenses 32 and 33 and a concentrated beam of light is directed onto a given point on the disk 36. The point at which the beam is concentrated depends entirely upon the position of the tube with relation

5 to the outer casing 10. This beam of light serves to expose that particular point of the disk 36 and results in a dark spot or dot on the exposed portion of said disk. The particular shape of the 10 recess 57 and the cam 55 controls the length of time that the circuit to the lamp 18 is closed and, as said cam continues its rotation, it will be evident that the plunger will move out of the recess 57, which results in a downward movement 15 of the plunger and an opening of the circuit by disengaging the switch arm 46 from the contact screw 50. After the lamp is extinguished, the device is removed from the well bore, after which the disk 36 is removed from the recess 35 of the 20 plug 16. By observing the spot on the disk, which spot was formed by exposing a portion of said disk to the concentrated light beam, it is possible to accurately determine the inclination of the outer casing from the vertical. Since the outer 25 casing's inclination is controlled by the inclination of the bore, it is manifest that the reading on the disk 36 gives an accurate indication of the angularity or inclination from the vertical of the bore at the point at which the reading was taken. The disk may be filed away and provides a 30 permanent record, which may be referred to at a later date.

It will be manifest that the entire device is simple in construction and the arrangement provides for the lamp 18 to be automatically illuminated and extinguished to record the inclination from the vertical. It is pointed out that the lens 32 could be eliminated, as shown in Figure 10. In this case, the light rays from the lamp 18 are directed downwardly through the conical tube or sleeve 25 and strike the projection lens 33 which concentrate said light in a fixed beam on the disk 36. Also, the lenses 32 and 33, or the single lens 33 could be supported by means other than the tube or sleeve as, for example, said lens may be suspended from a wire or other frame (not shown). So long as the lens is free to assume a true vertical position, irrespective of the inclination of the casing, the purposes of the invention will be accomplished. As before pointed out, the timing mechanism T may be of any desired construction, such as is used in watches and clocks. This mechanism may be readily adjusted to require a given predetermined length of time before the circuit to the lamp is closed. Thus, by adjusting the mechanism at the surface, sufficient time for lowering the device to a desired depth at which the reading is to be taken is had.

60 The foregoing description of the invention is explanatory thereof and various changes in the size, shape and materials, as well as in the details of the illustrated construction, may be made, within the scope of the appended claims, without departing from the spirit of the invention.

65 What I claim and desire to secure by Letters Patent is:

1. A device for determining the inclination of a well bore, including a casing lowerable through the bore, light sensitive medium carrying means in the casing, light ray concentrating means above said carrying means for directing light rays upon the medium, and to indicate upon the latter the position of the concentrating means with respect to the casing, means for mounting

the light ray concentrating means for universal pendulum-like movement relative to the casing, a source of light in the casing above the concentrating means to direct rays from the source into the concentrating means, and means to secure the source of light to the casing against movement relative thereto, whereby the source of light remains fixed during all movements of the concentrating means.

2. A device for determining the inclination of a well bore, including a casing lowerable through the bore, light sensitive medium carrying means in the casing, light ray concentrating means above said carrying means for directing light rays upon the medium, and to indicate upon the latter the position of the concentrating means with respect to the casing, means for mounting the light ray concentrating means for universal pendulum-like movement relative to the casing, a source of light in the casing above the concentrating means to direct rays from the source into the concentrating means, means to secure the source of light to the casing against movement relative thereto, whereby the source of light remains fixed during all movements of the concentrating means, wherein the concentrating means has an open upper end portion and wherein the source of light consists of an electric bulb which projects into said open upper end but is in such relation thereto so as to provide for swinging movements of the concentrating means while the bulb remains in fixed position.

3. A device for determining the inclination of a well bore, including a casing lowerable through the bore, light sensitive medium carrying means in the casing, light ray concentrating means above said carrying means for directing light rays

upon the medium, and to indicate upon the latter the position of the concentrating means with respect to the casing, means for mounting the light ray concentrating means for universal pendulum-like movement relative to the casing, a source of light in the casing above the concentrating means to direct rays from the source into the concentrating means, means to secure the source of light to the casing against movement relative thereto, whereby the source of light remains fixed during all movements of the concentrating means, wherein the concentrating means consists of a tubular member having a flared upper end, wherein the source of light consists of an electric bulb which projects into the flared upper end of the concentrating means and is in such spaced relation thereto to provide for all movements of the concentrating means while the electric bulb remains in its fixed position, and wherein the mounting means is disposed between said flared upper end of the concentrating means and the adjacent portion of the casing.

4. In a device for determining the inclination of a well bore of the type wherein a pendulum is universally suspended axially of an elongate enclosure having therein a light sensitive medium disposed below said pendulum, and wherein the pendulum is provided with a light projecting lens, the improvement which includes a light source mounted in the enclosure in stationary relation to the pendulum concentrically thereof and in position to direct a stream of light axially through said lens, whereby a slender beam of light is directed upon said light-sensitive medium and the pendulum may swing without swinging said light source.

LEONIDAS C. MILLER.
